UNITED STATES PATENT OFFICE.

ALEXANDER YAUCK, OF KANSAS CITY, MISSOURI.

COLLAR-BUTTON.

1,353,444.

Specification of Letters Patent. Patented Sept. 21, 1920.

Application filed March 4, 1920. Serial No. 363,290.

To all whom it may concern:

Be it known that I, ALEXANDER YAUCK, a citizen of Russia, and a resident of Kansas City, in the county of Jackson and State of Missouri, have invented certain new and useful Improvements in Collar-Buttons, of which the following is a specification.

This invention relates to improvements in means for securing collars to shirts at the back.

The objects are, first, to provide such device in form adapted to be applied to a shirt-band, in the back button-hole, it being made of material that will not discolor the garment and which is inexpensive to manufacture and easy to attach.

Second, to provide devices that can be used equally well with any style of collar, as standing, turn-down, high or low, and with less difficulty than the common detachable fastening means, the device being essentially flat so that it can be employed to button the back, avoiding the binding of the common buttons, leaving a free passage for adjusting a tie of the scarf type in the turn-down collar.

Third, to provide such devices having a tasteful and ornamental appearance and which, by reason of their peculiar thin flat shape, are worn with exceptional comfort and used with more facility than a detachable button, besides being always ready for use.

These and other allied objects are attained by the novel construction and configuration hereinafter fully set forth and shown in the accompanying drawings, forming a material part of this specification, and in which:—

Figure 1 is a perspective view, showing the application of the button.

Fig. 2 is an enlarged sectional view taken on line 2—2 of Fig. 1.

Fig. 3 is a front elevational view of the button in detail.

Fig. 4 is a side view of the same.

Referring to the drawings in detail, the numeral 10 designates a fragmentary portion of a conventional type of shirt such as is commonly worn by men, the same having a lining 11 at the band 12 and a doubled outer covering comprised of elements 13 and 14, these being connected by a row of stitches 15 at the outer edge, a similar row of stitches 16 being at the bottom of this band

except at the extreme rear where a pocket 17 is formed open at the bottom. 55

The front of the shirt is open along the bosom seams 18 and 19, the two sides being held together by an ordinary button or stud passing through the button holes 20. 60

The rear button hole 22 passes through the outer element 14 of the shirt band communicating with the pocket 17, the foregoing description being applicable to ordinary types of shirts in use. 65

The invention is comprised of an integral fastener made of a sheet or plate of thin non-corrodible metal, as silver, aluminum or plated as may be preferred, and shaped into an elliptical head 25 having its longer axis disposed horizontally and connected at its lower edge with a bar like strip 26 the curved end 27 of which extends upward parallel with and beyond the upper edge of the plate 25. 70

This plate 25 is formed convexly, its center portion 30 normally being nearly in contact with the strip 26, which is curved or bowed toward the plate throughout its entire length, as best seen in Fig. 4. 75

The lower portion of the plate 25, below the center 30 is curved slightly outward, forming a recess 28, and then joined by a sharp bend 29 to the strip 26. 80

In operation the strip or bar 26 is inserted through the button hole 22 until the end 27 contacts with the stitching 15, whereupon the sharp bend 29 is entered below the band element 14 into the space 17 holding the button shank or strip 26 firmly in engagement and the button hole of the collar passed over the extending head 25 in the same manner as an ordinary button but with the difference that the collar is drawn by spring pressure tightly against the band 90 due to the convexity of the head and obviously will be securely held without the usual protuberance of a stud or button as commonly used. 95

Having thus described my invention and set forth the manner of its construction and use, what I claim as new and desire to secure by Letters Patent, is:— 100

1. A button of the class described comprising a vertical strip adapted to be wholly embedded in a neck band, an oval head formed with said strip, said head being bent convexly and disposed approxi- 105

mately parallel to said strip, and resilient integral connecting means extending between said strip and head, said head being adapted to pass through the button-hole of a collar.

2. A button of the class described comprising an outwardly curved strip having a sharp reentrantly turned bend at its lower

end adapted to be bodily inserted in a neck band, an oval head integrally joined at its 10 lower edge to said strip by the bend, the long diameter of said head being transverse and adjacent to said strip above the bend.

In testimony whereof I have signed my name to this specification.

ALEXANDER YAUCK.
